Primary Examiner — Robert A Delehanty(74) *Attorney, Agent, or Firm* — Carter, DeLuca & Farrell LLP(57) **CLAIM**

The ornamental design for a sink, as shown and described.

DESCRIPTION

FIG. 1 is a front perspective view of a sink in accordance with the present design;

FIG. 2 is a front elevational view thereof;

FIG. 3 is a rear elevational view thereof;

FIG. 4 is a right side elevational view thereof;

FIG. 5 is a left side elevational thereof; and,

FIG. 6 is a top plan view thereof.

The broken lines shown are included for the purpose of illustrating a portion of the sink that form no part of the claimed design.

1 Claim, 4 Drawing Sheets(56)
